DIALING AID FOR VISUALLY HANDICAPPED

Ruth L. Barr, 53 Webster Acres,
Webster Groves, Mo. 63119

Filed Mar. 16, 1970, Ser. No. 21,926

Term of patent 14 years

Int. Cl. D14—03

U.S. Cl. D26—14

FIG. 4.

FIG. 5.

FIG. 1 is a top plan view of the dialing aid for visually handicapped showing my new design;

FIG. 2 is a bottom plan view of the dialing aid for visually handicapped shown in FIG. 1;

FIG. 3 is a sectional view taken along the line 3—3 of FIG. 1;

FIG. 4 is a view in perspective along a top surface of the dialing aid for visually handicapped corresponding to FIG. 1; and

FIG. 5 is a view in perspective along a bottom surface of the dialing aid for visually handicapped corresponding to FIG. 2.

I claim:

The ornamental design for a dialing aid for visually handicapped, as shown and described.
